UNITED STATES PATENT OFFICE

WALTER HÖFER, OF LEIFLINGHAUSEN, NEAR LUDENSCHEID, GERMANY

FASTENER-ATTACHING MACHINE

Application filed December 22, 1928, Serial No. 327,912, and in Germany March 23, 1927.

This invention concerns a machine for securing fastenings, including hinges and similar fittings to boxes made of wood, cardboard, thin sheet metal and other suitable material, for instance cigar boxes, cardboard boxes, etc., provided with a flat lid and with a lid provided with a rim, by inserting and bending over long and narrow tongues, which are made in one piece with the fastenings, hinges etc., or by inserting the tongues over their whole length without the bending operation.

The invention is shown, by way of example, in the drawing, in which

15 Figure 1 is a front elevation,

Figure 2 a side elevation partly in section,

Figure 3 a plan partly in section,

Figure 4 a section taken along the line 20 A—B of Figure 2.

Figures 5 to 14 show details.

The machine which, according to the drawing, is constructed in the form of a one-armed press with a machine body 1, a 25 base plate 2 and is provided with a double-armed lever 4, secured by bolt or bolts 3, which lever carries on the one side a transverse rod 5 and on the other side a counter-weight 6, and is adapted to be partly rotated 30 through the draw-rod 7 by foot pressure or in some other way. On the transverse rod 5 are secured, in an adjustable manner, short arms 8, and these are connected by joints with vertical spindles 9, which are 35 vertically located in guides 10 and carry at the lower extremity a driver 11. The guides 10 are arranged in an adjustable manner on a transverse slide body 12, connected with the machine body 1, and are adjusted 40 laterally through screw spindles 13 disposed in the said machine body, which spindles are connected by a threaded nut 14 with the guides 10.

Under each of the drivers 11 a carrying 45 member 15 for the fastener holders is mounted on the guide-rods 16 which are set each in a cross-head 17 connected with the spindles 9 and are inserted vertically in the guides 10. Between the latter and the members 15

50 a spring 18 is fitted on each of the guide-rods

16. For accurately guiding the members 15, guide pins 19 can be fitted in the base which cooperate with openings in the members.

In each of the members 15 a fastener holder 20 is located in a removable manner, 55 and is provided with a hole 21 corresponding to the fastenings, hinges, etc., to be attached as shown in Figures 4, 9 and 10. The fastenings, hinges, etc., have long narrow tongues, and for these corresponding grooves 60 22 are provided in the fastener holders 20. Through these grooves 22 the fastenings, hinges, etc., are accurately guided during the attaching operation.

In the base-plate 2, as shown in Figures 65 1 to 3 and 6, underneath the fastener holder 20 an anvil 23 is fitted in a displaceable manner, on which is placed, for instance, the cigar box 24, Figures 1 and 2, or any other object to be provided with fastenings, 70 hinges, etc.

In accordance with Figures 1 and 2, fastening members 25 as per Figure 12 are to be attached the cigar box 24 or the like, which members are provided with long pointed 75 tongues 26. In the fastener holders 20 the fastening member 25 is inserted for this purpose and then, by foot pressure or otherwise, the lever 4 is drawn downwards with the front arm. The spindles 9 are thereby moved 80 downwards in a precisely vertical direction with the drivers 11, the guide-rods 16 and the members 15 with the fastener holders 20 and the fastening members 25 etc. disposed therein, until the members 15 rest on the cigar 85 box 24 or the like. The spindles 9 with the drivers 11 then continue their downward movement alone, whereby the fastening members 25 are pressed through the fastener holders, the tongues 26 of the latter are inserted in the cigar box 24 or the like and bent under or on the inside, as shown in Figure 11. Thereupon, the working parts return to the position indicated.

The drivers 11 are formed according to the 95 shape of the fastening members or fastenings, hinges etc., and are provided on the sides with ribs which fit in the grooves 22 of the fastener holders 20.

According to Figure 6, a hinge 27 as per 100

Figure 13 is attached. When applying the fastening to the cigar box 24 or the like, a strip 28 is secured to the base-plate 2, while the lid 29 rests on the anvils 23.

5 For attaching a fastening 30 as per Figure 14, a plate 31 as per Figure 7 is secured to the base-plate 2, on which plate the lid 29 rests, while the cigar box 24 or the like rests on a strip connected with the plate 31.

10 For cigar boxes, receptacles, etc., the lid of which is provided with a rim, as shown in Figure 8, a frame 33 is secured to the base-plate 2, and on this frame are disposed, in a displaceable manner, two anvils 34, on which 15 the rim of the lid 29 and of the box 24 or of the receptacle or the like rests, as shown in Figure 8.

Fastenings, hinges or the like of a form other than those represented can, of course, 20 be attached. According to the distance required between them, the levers 8, spindles 9, guides 10, fastener holder carrying members 15 and the anvils 23 or 34 are adjusted.

On the machine body 1 a guide 36 is secured, which has a regulating screw 36. 25 Through the regulation of the latter, the stroke of the lever 4 can be adjusted according to the thickness of the cigar boxes, receptacles, etc. As a result the pressure of the 30 driver 11 is not too heavy, and the wood, cardboard, etc., of the cigar boxes or the like, will not split.

The machine can also be used for attaching only one fastening member, hinge, etc., at a 35 time. In this case a lever 8, a spindle 9, guide 10 etc., are brought as near as possible to the body 1, and in the corresponding fastener holder 20 only one fastening member, hinge or the like, is inserted.

40 Having now described my invention, what I claim and desire to secure by Letters Patent is—

1. A machine for attaching fasteners, provided with penetrating tongues, to boxes comprising in combination a machine body, a machine base, spindles movable in a vertical plane, tools carried at the end of said spindles, guides for said spindles, means for effecting lateral movement of the guides, a 45 common lever, arms rigidly connected at their one ends to said common lever, and jointedly connected at their other ends to the spindles, fastener holders guided on the machine body, and means for oscillating said common lever to effect the vertical movement of the spindles towards and away from the fastener holders.

2. A machine for attaching fasteners, provided with penetrating tongues, to boxes comprising in combination a machine body, a 60 machine base, spindles movable in a vertical plane, guides for said spindles, a lateral rigid slide body for said guides, screw spindles for effecting lateral displacement of said guides, a common lever, arms rigidly connected at their one ends to said common lever and

jointedly connected at their other ends to the spindles, fastener holders guided on the machine body, and means for oscillating said common lever to effect the vertical movement of the spindles towards and away from the fastener holders. 70

3. A machine for attaching fasteners, provided with penetrating tongues, to boxes comprising in combination a machine body, a machine base, spindles movable in a vertical plane, tools carried at the end of said spindles, guides for said spindles, means for effecting lateral movement of the guides, a common lever, arms rigidly connected at their one ends to said common lever by means of a transverse rod carried at the one end of said common lever and jointedly connected at their other ends to the spindles, fastener holders guided on the machine body, and means for oscillating said common lever to effect the vertical movement of the spindles towards and away from the fastener holders. 75 80 85

4. A machine for attaching fasteners, provided with penetrating tongues, to boxes comprising in combination a machine body, a machine base, spindles movable in a vertical plane, tools carried at the end of said spindles, guides for said spindles, means for effecting lateral movement of the guides, a common lever, arms rigidly connected at their one ends to said common lever and jointedly connected at their other ends to the spindles, fastener holders guided on the machine body, a vertical guide rod located in the vertical guides, cross-heads connecting said guides with the vertical spindles, and means for oscillating said common lever to effect a vertical movement of the spindles towards and away from the fastener holders. 90 95 100

5. A machine for attaching fasteners, provided with penetrating tongues, to boxes comprising in combination a machine body, a machine base, spindles movable in a vertical plane, tools carried at the end of said spindles, guides for said spindles, means for effecting lateral movement of the guides, a common lever, arms rigidly connected at their one ends to said common lever and jointedly connected at their other ends to the spindles, fastener holders guided on the machine body having apertures therein in the form of the fastening to be fixed, grooves in said fastener holders to accommodate the penetrating tongues of said fastenings, and means for oscillating said common lever to effect the vertical movement of the spindles towards and away from the fastener holders. 110 115 120

6. A machine for attaching fasteners, provided with penetrating tongues, to boxes comprising in combination a machine body, a machine base, spindles movable in a vertical plane, drivers carried at the ends of said spindles, said drivers being provided with ribs adapted to correspond with the penetrating tongues of the fastenings, guides for said 125 130

- spindles, means for effecting lateral movement of the guides, a common lever, arms rigidly connected at their one ends to said common lever and jointedly connected at 5 their other ends to the spindles, fastener holders guided on the machine body, and means for oscillating said common lever to effect the vertical movement of the spindles towards and away from the fastener holders.
- 10 7. A machine for attaching fasteners, provided with penetrating tongues, to boxes comprising in combination a machine body, a machine base, a plate for supporting the boxes, spindles movable in a vertical plane, 15 tools carried at the end of said spindles, guides for said spindles, means for effecting lateral movement of the guides, a common lever, arms rigidly connected at their one ends to said common lever and jointedly connected at their other ends to the spindles, fastener holders guided on the machine body, and means for oscillating said common lever to effect the vertical movement of the spindles towards and away from the fastener holders.
- 20 8. A machine for attaching fasteners, provided with penetrating tongues, to boxes comprising in combination a machine body, a machine base, a frame for supporting the lid of the box, spindles movable in a vertical plane, tools carried at the end of said spindles, guides for said spindles, means for effecting the lateral movement of the guides, a common lever, arms rigidly connected at their one ends to said common lever, and 25 jointedly connected at their other ends to the spindles, fastener holders guided on the machine body, and means for oscillating said common lever to effect the vertical movement of the spindles towards and away from the fastener holders.
- 30 9. A machine for attaching fasteners, provided with penetrating tongues, to boxes comprising in combination a machine body, a machine base, spindles movable in a vertical plane, tools carried at the end of said spindles, guides for said spindles, means for effecting lateral movement of the guides, a common lever, arms rigidly connected at their one ends to said common lever and jointedly 35 connected at their other ends to the spindles, a guide for said lever, a regulating screw to limit the stroke of said lever, fastener holders guided on the machine body, and means for oscillating said common lever to effect the vertical movement of the spindles towards and away from the fastener holders.
